UNITED STATES PATENT OFFICE.

FREDERIC W. HILLARD, OF NEW YORK, N. Y.

TYPE-WRITING MACHINE.

SPECIFICATION forming part of Letters Patent No. 758,252, dated April 26, 1904.

Application filed October 6, 1903. Serial No. 175,992. (No model.)

To all whom it may concern:

Be it known that I, FREDERIC W. HILLARD, a resident of Tottenville, in the borough of Richmond, city and State of New York, (whose 5 post-office address is 287 Broadway, New York city,) have invented certain new and useful Improvements in Type-Writing Machines, of which the following is a specification.

My invention is an improvement in the type-bar system of type-writing machines wherein the several type-heads are each provided with two (or more) printing characters arranged, respectively, for upper and lower case printing by the usual sidewise movement either of 15 the platen relatively to the type-bars or of the type-bars relatively to the platen.

In the drawings I have only shown those parts which are necessary to illustrate the invention; but I intend to apply the invention 20 to a "visible-writing machine," preferably of the style shown in the drawings herein.

The invention is also particularly applicable to "front-strike" type-writers of the well-known Underwood style.

25 In the drawings which form a part of this specification, Figure 1 is a front view of the type-bar frames with one type-bar shown in the printing position and several other bars in their positions of rest, many of the bars and 30 their hangers being removed from the frames and not shown. The figure also shows the platen or printing-cylinder. Fig. 2 is a diagrammatic view of the whole set of type-bars developed or spread out in a plane with the 35 several type-bars arranged in the same order relatively to each other that they are arranged in when in the machine. Fig. 3 is a front view showing one method of mounting my system of type-bars in a machine. Fig. 4 is a side view of the machine shown in Fig. 3.

The platen 1 is hung in the carriage, as usual, and moves with the carriage lengthwise of the platen from side to side of the machine when the machine is operated for printing. The 45 type-bars 2 are pivotally mounted in the hangers 3. The hangers 3 are respectively clamped to the several type-bar frames 4, 5, and 6, and each hanger has a slight individual adjustment to compensate for imperfections in the 50 lengths of the several bars, as is usual. The

hangers in central frame 5 are screwed to the frame side by side in the arc of a circle concentric with the printing-point; but the pivots for the type-bars are placed, in the well-known Remington style, alternately near the 55 upper and lower faces of the hangers, so that the pivots lie alternately above and below each other in the arc of the circle to allow greater length for the several type-bar pivots.

In Figs. 3 and 4 I have illustrated my preferred method of connecting the several type-bars 2 with their respective key-levers 8. A connecting-wire 9 is hooked at its lower end into the short arm of each type-bar, and at its upper end each connecting-wire is hooked into 60 the arm *c* of rock-shaft 10, each rock-shaft being provided with a rocker-arm *c*, into which the connecting-wire 9 is hooked, and with a rocker-arm *d*, into which is hooked the upper end of the connecting-wire 11, which serves to 65 connect each rock-shaft with its key-lever 8. The rocker-arms *c d* are placed on the opposite sides of the rock-shafts, so that when the connected key-lever is depressed, as by a blow 70 on a key 12, thus pulling down the connecting-wire 11, together with the arm *d*, and rocking the rock-shaft 10, the arm *c* will be lifted, thus lifting the connecting-wire 9 and the short arm of the type-bar into which it is hooked and 75 swinging the long arm of the type-bar and the 80 type-head 7 thereon to the printing-point at the platen 1.

In Fig. 1 the platen is shown in full lines in the lower-case position and in dotted lines in the upper-case position. When at the 85 printing-point, each type-head 7 stands perpendicular to the line of print, as shown in Fig. 1, and therefore the several type-heads are mounted on their respective bars at varying angles corresponding to the respective 90 positions of the several type-bars about the printing-point. Thus the type-heads on the bars below the printing-point and in line therewith on frame 5 are parallel to their bars or approximate to parallel therewith, while the 95 type-heads on the bars to the left and to the right of the central bars incline from parallel with their bars in successively-increasing oblique angles toward both ends of the frame; but on none of the bars in frame 5 is the ob- 100

liquity of the type-heads so great but that the several bars thereon can be of substantially uniform lengths and pivoted in the arc of a circle concentric with the printing-point, as I have shown them in the drawings, so that the several heads can lie snugly side by side when at rest at substantially uniform distances from the printing-point, although the heads on the bars at either end of the frame slightly overlap one another. If, however, the central frame were made to extend through a much greater arc, the type-heads on the bars farther around toward the sides of the machine would overlap one another to such a degree as to collide with each other if they were arranged to lie snugly side by side, as they do in frame 5. The main purpose of my invention is to avoid this difficulty, which I do by providing series of heads on the bars at the sides of the machine which not only overlap each other, but also overreach each other, as I will now describe.

On the side frames 4 and 6 the type-heads on the bars which are pivoted in the central part of the frames directly to the left and directly to the right of the printing-point are mounted substantially perpendicular to their bars, while the heads on the bars above and below said central bars, although not mounted perpendicularly to their bars, are mounted thereon at considerable obliquity from parallel, so that, considered as a series, the type-heads on the bars below the line of print in either frame 4 or 6 cannot lie snugly together side by side when at rest at equal distances from the printing-point, and the same is true of the heads on the bars above the line of print. Therefore in order that the type-heads on frames 4 and 6 may lie snugly side by side I have so arranged their bars that the several heads will overlap each other and also overreach each other at successively-varying distances from the printing-point when at rest. Thus the type-head on the bar which is pivoted next adjacent to the line of print is approximately perpendicular to its bar and is overlapped and overreached by the type-head on the bar pivoted the second one away from the line of print, which in turn is overlapped and overreached by the third head away from the line of print, and so on to the head of the bar which is pivoted at the end of its series most remote from the line of print. Therefore the head on any intermediate bar in a side series overlaps and overreaches the head lying next it on one side and is overlapped and overreached by the head lying next it on the opposite side. I use the term "overreach" in the sense of reaching above or lying farther away from the printing-point. It is obvious that the overreaching of the adjacent heads counteracts the overlapping of the heads in the side series and enables me to pack them as snugly together without crowding as they can be packed in the central series on frame 5. It is also ap-

parent that the head that is nearest to perpendicular with its bar is overreached by all of the other heads in its series and that successively each head overreaches all of the heads that are nearer than it to perpendicular with their bars and is in turn overreached by all the heads in the series which are more oblique than it from perpendicular to their bars. Hence I mount the head next adjacent to the line of print on the shortest bar and the succeeding heads on successively-longer bars to the end of the series most remote from the line of print. Accordingly in the two series, the one in frame 4 and the other in frame 6, above the line of print the longest bar is the uppermost one and the shortest bar the lowermost one in its series, while in the two series below the line of print the order is reversed, the lowermost bar being the longest one in its series and the uppermost one the shortest in the series.

My entire system of type-heads and type-bars, as shown in the drawings, embraces five series — viz., first, a central series (on frame 5) below and in front of the printing-point, in which all of the bars are substantially uniform in length and pivoted at equal distances from the printing-point, with the type-heads thereon either parallel with their bars or only slightly oblique from parallel, so that they can lie snugly side by side at equal distances from the printing-point; second, two side series (on frame 4) the one above and the other in reverse order below the line of print at the left of the printing-point, comprising bars of successively-varying lengths pivoted at successively-varying distances from the printing-point, with the shortest bar in each series pivoted next adjacent to the shortest bar in the series on the opposite side of the line of print, with the type-heads on these two shortest bars the nearest to perpendicular to their bars of any in their respective series and lying end to end with each other on the opposite sides of the line of print and overlapped and overreached by the succeeding type-heads in their series and with the several heads in the series all mounted at considerable obliquity from parallel with their bars, so that they cannot lie snugly side by side at equal distances from the printing-point, but can snugly overlap and overreach each other and lie side by side at varying distances from the printing-point, and, third, two similar side series of bars and heads at the right of the printing-point, (in frame 6.) By thus systematizing and positioning the type-bars and type-heads in the several side series I am enabled to provide the largest possible clearance-room for the type-heads, because the upwardly-projecting end of each type-head overreaches and overlaps the downwardly-projecting end of the next adjacent head and the upwardly-projecting end of the one head is always on the longer and the downwardly-projecting end of

the other on the shorter of two adjacent bars, so that the amount of clearance-room between two adjacent heads is always the difference between the length of the longer bar plus the distance its head inclines upward and the length of the shorter bar minus the distance its head inclines downward—that is, by making the shortest end of each series the one next adjacent to the line of print I cause the upwardly-extending end of the head on each succeeding longer bar when alined for printing to overreach and overlap the downwardly-extending end of the head on each preceding shorter bar, thus securing double clearance-room. This order cannot be reversed without sacrificing the clearance-room, for if the longest bars in the side series were placed next adjacent to the line of print it is obvious that the downwardly-extending end of each head

would be on the longer bar and would interfere with and collide with the upwardly-extending end of the head on the next succeeding shorter bar. By thus systematizing and positioning the type-bars and type-heads I also preserve a medium length for a large proportion of the bars, because by my arrangement all of the bars in the central series on frame 5 are of the medium length, as well as the central bars in the four side series in frames 4 and 6. In its broader aspect my invention comprises a central series of type-bars and one or more side series at each end of the central series, with the type-bars in the side series successively varying in length and the shortest bar in either side series mounted the nearest one in its series to the line of print. By a "central series of type bars" I mean a series comprising a plurality of type-bars in a group so arranged and placed in the machine that a line drawn perpendicular to the line of print and passing through the printing-point will bisect the series. Preferably, but not necessarily, such central series comprises type-bars all substantially uniform in length and pivoted, as I have shown them, in the arc of a circle concentric with the printing-point; but I do not intend to limit my claims to such preferred form, excepting where they are in terms so limited.

I do not in this application claim the mechanism connecting the type-bars and key-levers shown herein, as the same forms the subject-matter of my prior application, Serial No. 603,845, filed August 25, 1896.

Having thus described my invention, what I claim, and desire to secure by Letters Patent, is—

1. The combination, with a plurality of type-bars mounted in a central series, of a side series at each end of said central series, comprising a plurality of type-bars of successively-varying lengths, with the longest bars in each of said side series longer than any bar in said central series and mounted at the ends of their respective series next adjacent to the said central series, substantially as described.

2. The combination, with a plurality of type-bars mounted in a central series, of a side series at each end of said central series, comprising a plurality of type-bars of successively-varying lengths, with the shortest bars in each of said side series shorter than any bar in said central series and mounted at the ends of their respective series farthest from the said central series, substantially as described.

3. The combination, with the type-bars, of a central series of type-heads thereon each bearing a plurality of characters, arranged to print at a common point and to lie side by side when at rest, and two series of type-heads, arranged the one in reverse order of the other, at each end of said central series, each bearing a plurality of characters, arranged to overlap and overreach each other when at rest and to print at said common point, substantially as described.

4. The combination, with a central series of type-bars of substantially uniform lengths, of two side series of type-bars at each end of said

5. distance its head inclines upward and the length of the shorter bar minus the distance its head inclines downward—that is, by making the shortest end of each series the one next adjacent to the line of print I cause the upwardly-extending end of the head on each succeeding longer bar when alined for printing to overreach and overlap the downwardly-extending end of the head on each preceding shorter bar, thus securing double clearance-room. This order cannot be reversed without sacrificing the clearance-room, for if the longest bars in the side series were placed next adjacent to the line of print it is obvious that the downwardly-extending end of each head

20 would be on the longer bar and would interfere with and collide with the upwardly-extending end of the head on the next succeeding shorter bar. By thus systematizing and positioning the type-bars and type-heads I also preserve a medium length for a large proportion of the bars, because by my arrangement all of the bars in the central series on frame 5 are of the medium length, as well as the central bars in the four side series in frames 4 and 6.

I preferably make the longest bar in each series in the frames 4 and 6 longer than the bars in frame 5, which latter are all of substantially uniform length, and the shortest bar in each of frames 4 and 6 shorter than the bars in frame 5, securing by this arrangement the largest clearance without unduly varying the lengths of the several type-bars in the machine.

40 In the drawings I have shown the type-bars so arranged that the type-heads utilize practically all of the clearance room in about three-quarters of the angular space surrounding the printing-point, leaving the upper 45 quarter thereof open. In this arrangement the portion of the line of print back of frames 4 and 6 is out of view of the operator, the printing-point and remainder of the line of print being in view of the operator when 50 printing. In case it should be desirable to bring the entire printing-line in view of the operator while printing it is obvious that this can readily be accomplished by making the frames 4 and 6 each in two parts, cutting 55 away the portions thereof in front of the printing-line, and removing the two shortest type-bars and their hangers 3 from the machine.

In the drawings I have indicated the lower-case characters on the type-heads 7 by the reference-letter *a* and the upper-case characters by the reference-letter *b*, the entire set of lower-case characters *a* and upper-case characters *b* being alined in the machine to 65 all print at the common printing-point.

central series, the one on one side of the line of print and the other in reverse order on the opposite side, each comprising a plurality of type-bars of successively-varying lengths, 5 with type-heads mounted obliquely thereon and each bearing a plurality of characters arranged to print at a common printing-point, and to lie, when at rest, overlapping and over-reaching each other, the arrangement being 10 such that the type-head which is mounted on any bar of a side series overreaches all of the type-heads in the series which are mounted on shorter bars and is overreached by all of the type-heads which are mounted on longer bars. 15 5. The combination, in a central series of type-bars, of type-heads thereon each bearing a plurality of characters arranged to print at a common printing-point, and to lie, when at rest, side by side at substantially uniform distances from said printing-point, and a side series of type-bars at each end of said central series, the type-heads on said side series each bearing a plurality of characters arranged to print at said printing-point, and to lie, when 20 at rest, the one overlapping and over-reaching the other, with the type-head on the type-bar, in each of the two said side series, which is pivoted next adjacent to the central series, lying the farthest in its series from the printing-point and farther therefrom than the type-heads in said central series, substantially as 25 described.

6. The combination, in a central series of type-bars, of type-heads thereon each bearing a plurality of characters arranged to print at a common printing-point, and to lie, when at rest, side by side at substantially uniform distances from said printing-point, and a side series of type-bars at each end of said central 30 series, the type-heads on said side series each bearing a plurality of characters arranged to print at said printing-point, and to lie, when at rest, the one overlapping and over-reaching the other, with the type-head on the type-bar, in each of said side series, which is pivoted 35 the most remote in its series from the central series, lying the nearest in its series to the printing-point and nearer thereto than the type-heads in said central series, substantially as 40 described.

7. The combination, with a central series of type-bars, of two side series of type-bars, arranged the one in reverse order to the other, at both ends of said central series, the type-heads on the bars in the several side series each bearing a plurality of characters arranged to print at a common printing-point, and to lie, when at rest, the one lapped over the other at 45 successively-varying distances from the printing-point, with the type-heads on the type-bars which are pivoted next adjacent to each other in the two side series at one end of said central series, lying, the nearest in their series to the printing-point, substantially as 50 described.

8. The combination of a plurality of type-bars all of substantially uniform length and pivoted in a central series in the arc of a circle concentric with the printing-point, and a plurality of type-bars of successively-varying 70 lengths pivoted in a series at each end of said central series, with the longest bar in each of the two last-mentioned series longer than the bars in said central series and pivoted at the ends of their respective series next adjacent to 75 said central series, substantially as described.

9. The combination of a plurality of type-bars all of substantially uniform length and pivoted in a central series in the arc of a circle concentric with the printing-point, and a 80 plurality of type-bars of successively-varying lengths pivoted in a series at each end of said central series, with the shortest bar in each of the two last-mentioned series shorter than the bars in said central series and pivoted at the 85 ends of their respective series farthest from said central series, substantially as described.

10. The combination of a series of type-bars arranged to print at a common point and pivoted in the arc of a circle concentric with the 90 printing-point, and two series of type-bars at one end of said first-mentioned series, mounted the one series on one side of the printing-line and the other series in reverse order on the opposite side of the printing-line, the type-bars in said two last-mentioned series being 95 arranged to print at said common point and pivoted at successively-varying distances therefrom, and type-heads on said bars each bearing a plurality of characters, substantially as 100 described.

11. The combination of a plurality of type-bars all of substantially uniform length and pivoted in a series in the arc of a circle concentric with the printing-point, and a series 105 of type-bars of successively-varying lengths at each end of said first-mentioned series, the longest bar in each of the two last-mentioned series being longer than, and the shortest bar shorter than the bars of said first-mentioned 110 series, substantially as described.

12. The combination of a plurality of type-bars all of substantially uniform length, pivoted in a series in the arc of a circle concentric with the printing-point, and a plurality 115 of type-bars of successively-varying lengths pivoted in two series, the one series on one side of the printing-line and the other series in reverse order on the opposite side of the printing-line, at one end of said first-mentioned series, the longest bar in each of the two latter series being longer than, and the shortest bar shorter than the bars of said first-mentioned series.

Signed by me in New York city this 3d day 125 of October, 1903.

FREDERIC W. HILLARD.
